PROCESS AND APPARATUS FOR THE
MANUFACTURE OF PULPCarl Busch Thorne, Hawkesbury, Ontario,
CanadaApplication April 27, 1933, Serial No. 668,209,
and in Canada April 20, 1932

8 Claims. (Cl. 92—7)

This invention relates to the manufacture of pulp and particularly to an improved process and apparatus therefor.

The object of the invention is to effect economies in the manufacture of pulp by utilizing in an advantageous and convenient manner the heat contained in the materials discharged from both the digester and the blow pit.

Proposals have heretofore been made for the recovery of heat from the digester relief gases but insofar as applicant is aware there are no previous arrangements whereby full advantage may be taken of all the heat available in treated pulp as well as in the relief gases and the present invention provides a simple practical method and apparatus therefor.

The invention will now be described with reference to the accompanying drawing, which illustrates in sectional elevation apparatus for carrying out the invention.

1 represents any suitable digester as commonly used for cooking wood chips in the manufacture of sulphite pulp. 2 indicates any convenient recipient or separator tank into which the relief acid from the digester 1 is discharged through a pipe 3. In this tank the free gases are separated from the liquor and the gases are led off along a pipe 4 while the liquor flows down through a pipe 5. 6, 7 and 8 are heat exchangers consisting of a number of pipes made of acid resisting material, through which hot liquid or gas flows, these pipes being surrounded by a cooler liquid flowing in the opposite direction, thus absorbing the heat from the pipes. The heat exchangers are of ordinary construction and the pipes are indicated only on the exchanger 8.

A blowpit 9 is provided and may conveniently be of the type commonly used in pulp mills; that is, of the type comprising a tank having a perforated false bottom 10. The pulp at a high temperature is discharged from the digester 1 into the blowpit 9 through the blowpipe 11 controlled by a valve 12. The pulp is retained in the blowpit while the liquor drains down through the perforated false bottom 10 and passes through the pump 14 and pipe 15 to the heat exchanger 8. A valve 16 is provided in the pipe 15 and a discharge pipe 13 for wash water and the like leads to the sewer. Gases liberated in the blowpit may be conveyed to a desired absorption or recovery system through pipe 29.

Cold water, or other liquid to be heated, for example cooking liquor, is pumped under pressure into the top of the heat exchanger 8 through a pipe 18 while the hot liquor from the blowpit 9 is

pumped through the heat exchanger 8 in the opposite direction. The cold liquid to be heated flows over the outside of the exchanger pipes while the hot liquor is on the inside in the known manner. The heat from the liquor is thus transferred to the cold liquid. The liquid from the heat exchanger 8 passes through a pipe 19 to the heat exchanger 7 where it absorbs more heat from the hot liquor which is flowing through the heat exchanger from the recipient 2. The liquor from the heat exchanger 7 is allowed to go to the sewer. The water or other liquid from the exchanger 7 is carried through the pipe 20 to the exchanger 6 where it absorbs more heat from the gases from the recipient 2 as well as from the top relief gases from the digester flowing through a pipe 21. The liquid, which by this time will have reached a temperature of, say, 90 to 95° C. or more, as it leaves the heat exchanger 6, is carried through a pipe 22 to a tank, not shown, for use as required. The gas from the heat exchanger 6 flows along a pipe 23 to any suitable recovery tower or other apparatus as desired.

It may be very important when water is being heated in the heat exchangers, that the water should be free from any trace of acid, and in such instances there must be no leakage of acid or gas out from the pipes into the water. When it is necessary to accomplish this, the pressure outside of the exchanger pipes is always kept at a pressure which is greater than the pressure inside the pipes. In this way if there should be any break or leak in the pipes carrying the acid, then the liquid will lead into the acid and not the acid into the water.

To accomplish this, a pressure relief valve 24 is placed in the water line 22 as it leaves the last heat exchanger 6 and this valve may be regulated so that the pressure on the water in the system is always kept at a pressure which is higher than that of the hot fluids in the system. A check valve 18' may be provided in the supply pipe 18 to prevent reduction of pressure in the event of failure of the pump supplying the liquid to be heated.

In addition to this, a thermostatically controlled valve 25 may also be provided in the water line 22, a controlling thermometer 26 being placed in the heat exchanger 6. This valve 25 is of known construction and may be set to open at any desired temperature, for instance 90° to 95° C., and will close as soon as the temperature drops below this point.

In this way the pressure of the water, as well

as the temperature of the water, are controlled as desired.

In mills wherein the hot liquor is not drained into a blowpit, the heat may be recovered by means of an arrangement such as that indicated in dotted lines to the right of Figure 1. In this case, the gas which is given off during cooking is relieved through the pipe 21, and the excess cooking liquor is relieved through the pipe 3, as already described. Now, instead of opening the valve 12 in the blowpipe 11 and dumping the whole charge of the digester into the blowpit, a valve in the pipe 21 is fully opened and the gas is allowed to escape through the heat exchanger 6 until the pressure is reduced practically to atmospheric. A valve 15^b in pipe 15^a is now opened and the liquor in the digester is allowed to drain through a strainer bottom 35, through the pipe 15^a and the heat exchanger 8^a. When all of the liquor has drained off, then a water spray 36 is opened and the water washes the pulp in the digester, the water descends and leaves the digester through the pipe 15^a. In this way the heat from the liquor is recovered in the heat exchanger 8^a. After the pulp is washed inside the digester, the valve 15^b is closed, and the valve 12 in the pipe 11 is opened and the pulp is allowed to discharge into the blowpit 9 or into any other tank for further processing in the mill. The liquid to be heated enters exchanger 8^a through a pipe 18^a which may be fitted with a check valve 18", and, after being heated in the exchanger, passes on through pipe 19^a to exchangers 7 and 6 to be further heated as hereinbefore described. When this arrangement is employed the exchanger 8, and pipes 18 and 19 are omitted.

It will be apparent that the heat exchangers 6 and 7 may be combined in one unit or that a larger number of heat exchangers may be used to obtain the same result. While the use of the separator 2 is preferred, it may be omitted and the gas and liquor together may pass through the heat exchangers.

I claim:

1. A process of manufacturing pulp, which comprises cooking materials in a digester, passing fluids relieved from the upper part of the digester through heat exchanger means to recover heat therefrom, and, after the cooking operation has been completed, discharging solids and liquids from the bottom of the digester into a blowpit, draining the liquids from said blowpit and passing them through heat exchanging means, and circulating liquid to be heated through said heat exchanging means in counter-current to the hot fluids from the digester.

145

2. A process of manufacturing pulp, which comprises cooking materials in a digester, passing fluids relieved from the upper part of the digester through heat exchanger means to recover heat therefrom, and, after the cooking operation has been completed, discharging solids and liquids from the bottom of the digester into a blowpit draining the liquids from said blowpit and passing them through heat exchanging means, circulating liquid to be heated through said heat exchanging means in counter-current to the hot fluids from the digester, and automatically maintaining the liquid to be heated at a higher pressure than the fluids from the digester.

80

3. A process as claimed in claim 4, wherein the final temperature of the liquid to be heated is automatically maintained above a predetermined figure.

85

4. A process of manufacturing pulp, which comprises cooking materials in a digester, discharging fluid from the upper part of the digester, separating the last mentioned fluids into liquid and gaseous components, passing said fluid components through separate heat exchangers, and, after the cooking operation is complete, discharging solids and liquids from the bottom of said digester into a blowpit, draining the liquids from said blowpit and passing them through a heat exchanger, and circulating liquid to be heated successively through said heat exchangers.

90

5. A process as claimed in claim 4, wherein the pressure of the liquid to be heated is automatically maintained above the pressure of the fluids from the digester.

100

6. A process as claimed in claim 4, wherein if the final temperature of the liquid to be heated falls below a predetermined figure, the circulation of the liquid to be heated is automatically stopped until said predetermined temperature is again reached.

110

7. Apparatus for manufacturing pulp, comprising a digester, a blowpit having an outlet and a connection to said digester, heat exchanging means connected to said outlet, further heat exchanging means connected to the upper part of the digester, and pipes for circulating liquid to be heated successively through said heat exchanging means.

120

8. Apparatus as claimed in claim 7, wherein an automatic thermostatically controlled valve is provided to stop the circulation of the liquid to be heated when the temperature of said liquid falls below a predetermined limit.
